Des. 223,431

Patented Apr. 18, 1972

223,431

ELECTRIC CONTROL KEY

Dan C. Muessel, Stamford, Conn., and William Eisenreich, White Plains, N.Y., assignors to Eaton Yale & Towne Inc., Cleveland, Ohio

Filed Dec. 9, 1970, Ser. No. 26,367

Term of patent 14 years

Int. Cl. D8—06

U.S. Cl. D8—136

FIG. 1 is a side elevational view of an electric control key showing our new design;

FIG. 2 shows a longitudinal edge view thereof;

FIG. 3 is an elevational view showing the opposed side thereof;

FIG. 4 shows a rear end view;

FIG. 5 shows a front end view thereof; and

FIG. 6 is a side elevational view of an electric control key showing a further form of our new design.

We claim:

The ornamental design for an electric control key, substantially as shown.
